UNITED STATES PATENT OFFICE.

DAITAKE OKAMOTO, OF NORTH YAKIMA, WASHINGTON.

HAT AND CLOTHES HOOK.

1,305,560.

Specification of Letters Patent. Patented June 3, 1919.

Application filed January 13, 1919. Serial No. 270,823.

To all whom it may concern:

Be it known that I, DAITAKE OKAMOTO, a subject of the Emperor of Japan, residing at North Yakima, in the county of Yakima and State of Washington, have invented certain new and useful Improvements in Hat and Clothes Hooks, of which the following is a specification.

This invention relates to garment hooks; 10 and its object is to produce a neat appearing, inexpensively constructed and efficient device of this character.

The invention consists in the novel construction, adaptation and combination of 15 parts, as will be hereinafter described and claimed.

In the accompanying drawings, Figure 1 is a longitudinal vertical sectional view of a 20 wall type of garment hook embodying my invention; Fig. 2 is a similar view in the form of a ceiling or hanger-hook; and Fig. 3 is a view partly in side elevation and partly in vertical section of the hook shown in Fig. 2.

25 Referring now to the wall hook illustrated in Fig. 1, the numeral 4 designates a body formed, preferably, in a single piece by casting the same from brass or other suitable metal. Said body comprises a wall 30 plate 5 from which project substantially horizontal tubular members or arms 6 and 7 connected, preferably, by a bracket member 8.

The upper member 6 is provided with a 35 cylindrical chamber 9 extending from its outer end 10 to a shoulder 11 whence extends a relatively small passage 12 to the rear face 13 of said body.

14 represents a hook having a shank 15 40 terminating in a stub 16 which is screw-threaded for engaging with a female thread 17 provided at the outer end of the chamber 9. A second hook 18 has its shank 19 connected in like manner by a screw-threaded 45 stub 20 engageable with a female thread 21 provided at the outer end of the cavity 22 in arm 7. Integral with and projecting from the stub 20 is a stem element 23.

In the hanger type of my invention, illustrated in Figs. 2 and 3, the body 4¹ comprises 50 an upright tubular member 24 having near its lower end laterally projecting arms 25 and 26. The arm 25 is formed at its outer end with a hook 27. The other arm 26, 55 similarly to the arm 7 of the other embodiment of the invention, is provided with a

cavity 22¹ having a female thread 21¹ at its outer end to accommodate the threaded stub element 20¹ of a hook 18¹, the stub 20¹ being also provided with a stem 23¹ (Fig. 3) projecting therefrom. The member 24, like the member 6 (Fig. 1) is formed interiorly to provide a chamber 9¹ and a passage 12¹ respectively extending in opposite directions from a shoulder 11¹. 60

Fitting within the screw-threaded end of chamber 9¹ is a threaded stub 16¹ of a hook 14¹.

Included in the invention are means for securing the body of a garment hook to a 70 wall or ceiling and consisting of a rod 28 having at one end a head 29 through which extends diametrically a hole 29^a. The other end of said rod is tapered and provided with a worm or screw-thread 30. Adjacent the 75 threaded portion of the rod, the latter is formed to provide a collar 31, disposed so that when a rod is inserted in the body to have the collar seat against the shoulder 11 (Fig. 1), the threaded portion of the rod 80 will protrude from the rear face 13 of the body, and the rod-head 29 will protrude from the member 6, as in Fig. 1, or the member 24, as in Fig. 2, sufficiently far to expose the hole 29^a thereof in the associated member outside of the latter.

To accommodate the part of a rod head which protrudes from a member 6 (or 24) a recess 32 is provided in the stub and shank of the respective hook 14, or 14¹. 90

To secure the body 4 of my wall garment hook in place, the hook 14 is removed and with the stem 23 inserted as indicated by dotted lines in Fig. 1 through the hole 29^a of the rod head 29. The stem and associated hook are employed as indicated by 23^x and 18^x in Fig. 1, by the operator, as a handle to turn the rod and effect its being screwed into the wall until the face 13 of the body is brought firmly against the wall. 95 The hook 18 is then withdrawn from the rod hole 29^a and returned to its full-line position in arm 7 and the hook 14 secured to the member 6. 100

The device shown in Figs. 2 and 3 is applied in the same way with respect to a ceiling. To prevent the body being rotated about the axis of the securing rod, protuberances or wall-penetrating points such as 33 (Fig. 1) may advantageously be provided near the lower end of the wall piece 110 5; and, similarly, protuberances 33¹ are de-

sirably provided to project upwardly from the ceiling contact end 13¹ of the body 4¹ shown in Fig. 3.

What I claim, is—

- 5 1. In combination, a clothes hook comprising a body having a tubular member provided with a chamber extending from its outer end to a shoulder in proximity to the other end of the member and communicating with a passage extending from said shoulder to the adjacent face of the body, a rod extending through said member and engageable interiorly of the latter with said shoulder, said rod having a screw-threaded 10 end protruding from said passage and a head provided on the rod outside of said member for rotating the rod to cause the threaded end thereof to be screwed into or from a wall, and means engageable in the 15 outer end of said member to cover said rod head.
- 20 2. A clothes hook comprising a body having a tubular member and a tubular arm, hooks provided with stub elements engageable within the outer ends, respectively, of said member and arm, a stem provided on one of said stub elements, and means for attaching the clothes hook to a wall, said

means consisting of a rod having at one end a head provided with an aperture in which the aforesaid stem is engageable, a screw-thread at the other end of the rod, and means provided on the rod and engageable with the body interiorly of said tubular member.

35 3. A clothes hook comprising a body having a tubular member and a tubular arm provided at their outer ends with internal screw threads, hooks provided with threaded stub elements engageable with the respective internal screw threads, a stem provided on one of said stub elements, and means for attaching the clothes hook to a wall, said means consisting of a rod having at one end a head provided with an aperture in which the aforesaid stem is engageable, a screw thread at the other end of the rod, and means provided on the rod and engageable with the body interiorly of said tubular member.

40 45 Signed at North Yakima, Washington, this 31st day of Dec., 1918.

DAITAKE OKAMOTO.
